APPARATUS FOR FORMING A COVERING
ON AN INSULATED ELECTRICAL CON-
DUCTORBen K. Ford, Westfield, N. J., assignor to Western
Electric Company, Incorporated, New York,
N. Y., a corporation of New York

Application October 11, 1938, Serial No. 234,370

11 Claims. (Cl. 66—9)

This invention relates to an apparatus for forming a covering on an insulated electrical conductor, and more particularly to an apparatus for knitting an identifying covering on the conductor.

In various phases of the electrical art different methods are used to distinguish electrical conductors one from another. When a plurality of conductors are closely associated such conductors are frequently distinguishable by either braiding or knitting different colored coverings of textile cotton thread thereon. Braiding apparatus for accomplishing this result are well known. A knitting machine for forming such covering is shown in my copending application Serial No. 104,774 filed October 9, 1936, now Patent No. 2,126,250. In knitting such coverings on conductors it has been found that the field of distinguishing features may be greatly enlarged by using thread of different color combinations, the course of each thread forming readily noticeable portions extending longitudinally of the conductor.

Objects of the invention are to provide a simple, efficient and practical apparatus for forming an identifying covering.

With these and other objects in view, the invention comprises an apparatus for forming a knitted covering on an electrical conductor with certain of the thread courses differing in color and extending in zigzag paths longitudinally of the conductor. The apparatus comprises a rotary needle carrier, axially apertured for the advancement of the conductor therethrough, with needle actuating elements rotatable therewith and controlled by a cam, the cam being connected to a thread guide and conditioned to oscillate to cause the thread courses in the covering being formed to lie in irregular paths longitudinally of the conductor.

Other objects and advantages will be apparent from the following detailed description when taken in conjunction with the accompanying drawings, wherein

Fig. 1 is a vertical sectional view taken substantially along the line 1—1 of Fig. 2;

Fig. 2 is a horizontal sectional view taken along the line 2—2 of Fig. 1;

Fig. 3 is a fragmentary right hand side elevational view of that shown in Fig. 2, and

Fig. 4 is a fragmentary plan view of the covered conductor.

Referring now to the drawings, numeral 10 designates a housing support centrally apertured at 11 and having an integral tubular bearing 12 55

surrounding the aperture and extending downwardly into the support. An oscillating cam supporting element 13 is centrally apertured and has an integral tubular portion 14 extending through the bearing 12, where it receives, at its lower end, a retaining ring 15 secured to the tubular portion by suitable means such as a set screw 16. A ring gear 20 is disposed concentric with the tubular portion 14 and keyed thereto, as illustrated in Fig. 1. The ring gear is positioned between integral embossed portions on the cam supporting element 13 and the stationary housing 10, there being sufficient clearance between the ring gear and the embossed portion of the housing to allow 15 free rotation of the ring gear.

A hollow shaft 22 is disposed for rotation in the tubular portion 14 and has integral flange portions at its upper end, one of which rests upon the upper surface of the element 13 while the other is threaded to receive a nut 23 for securing a needle carrier 24 within the tubular shaft. The needle carrier has an integral interrupted annular flange receivable in an annular recess in the upper portion of the hollow shaft 22, where it is 20 locked in place by the nut 23.

Longitudinally extending grooves 26 in the needle carrier 24 receive needles 27 in circular spaced positions about a central aperture 28 in the needle carrier through which a core or electrical conductor 30, to be covered, passes. The needles 27 are, in the present embodiment, of the conventional latch type, with projections 31 thereon to operatively connect each needle with its respective lever or actuating element 32. The 35 levers 32 are pivotally supported at 33 by pivot supports 34 secured at spaced positions about a bracket 35 carried by the needle carrier to radially position the levers 32 about the axis of the needle carrier and in general alignment with their 40 respective needles. A slotted guide 37, also carried by the bracket 35, serves to hold the levers against lateral movement when the levers are rotated relative to their actuating cams 40 and 41. The cams 40 and 41 are mounted upon the 45 supporting element 13 and have lever engaging surfaces of contours provided to move the levers 32 to move each needle to a high position at the thread position hereinafter described, and to lower the needles to form stitches intermediate 50 the thread positions. The cams 40 and 41 are shown in detail in my aforementioned pending application.

Threads 45, 46, 47 and 48 are fed from spools (not shown), through eyelets 49, between friction discs 50 carried by pins 51, around the pins where

they are directed to their respective guides 52 and through the apertures therein. The eyelets 49 and the pins 51 are suitably mounted upon the bracket 55, as illustrated in Figs. 1 and 2, the bracket being supported by an upright 56 and adjustably secured thereto by a set screw 58. The upright 56 and a similar upright 57 are mounted upon the support 10 and have mounted upon their upper ends a cross member 60. A bearing 62 is formed adjacent the center of the cross member 60 to rotatably receive a sleeve 63 through which the conductor 30 passes. An oscillating member 65 is disposed upon the sleeve 63 and secured thereto. The outer ends of the oscillating member 65 are rigidly connected to the oscillating element 13 through the aid of vertical connecting bars 67, so that an oscillatory movement imparted to the element 13 will also be imparted to the member 65.

The sleeve 63 has an annular flange portion 70 integral therewith and apertured to adjustably receive the thread guides 52. A smaller tubular portion 71, integral with the flange 70, extends downwardly therebeneath and has a smaller portion tapered inwardly in substantially conical form to the lower end thereof which is positioned adjacent the upper end of the needle carrier 24. The flange 70 and the tubular portion 71 are also apertured for the free passage of the conductor therethrough.

Means for rotating the needle carrier 24 consists of a bevelled gear 75 fixed to the hollow shaft 22 at the lower end thereof, as shown in Fig. 1, and operatively connected to a power shaft 76 through a bevelled gear 77. The power shaft 76 is operatively connected to any suitable power means (not shown), and is rotated at a desired rate of speed to cause counterclockwise rotation of the shaft 22 and needle carrier 24, looking from the top of the apparatus shown in Figs. 1 and 2.

The means for imparting oscillatory movement to the cams 40 and 41 through their supporting element 13 and a like oscillatory movement to thread guides 52 consists, in the present embodiment, of a belt wheel 80 fixedly mounted upon the bevelled gear 75 to rotate therewith and cause rotation of a vertical shaft 81 through a connection of a belt 82 and a belt wheel 83, the latter being mounted upon the shaft 81. The shaft 81 is journalled in bearings in the support 10 and is caused to actuate an eccentric 84, as illustrated in Figs. 1, 2 and 3. The eccentric 84 is adjustably connected to a bell-crank lever 87, pivoted at 88, and operatively connected to a gear segment 89 through a link 90, the gear segment being pivoted at 91. The gear 89 interengages the ring gear 20 to cause intermittent rotation in reverse directions during the actuation of the eccentric 84.

Considering now the operation of the apparatus, let it be assumed, for the purpose of illustration, that the needle carrier 24 is being rotated through its driving means and that the oscillating means is at rest or disconnected from the driving means by the removal of the belt 82 from the belt wheels 80 and 83. Rotation of the needle carrier 24 will cause movement of the levers 32 relative to the cams 40 and 41, resulting in actuation of the needles to successively engage the threads at each of the four thread positions. In the present illustration the thread supplies 52 and the cams 40 and 41 are stationary, while the needle carrier is rotated, causing each needle to form a loop at each thread posi-

tion in the process of forming a knitted covering on the conductor 30 during the advancement of the conductor at a desired rate of speed through the machine. The covering thus formed on the conductor from the four threads shown in the present embodiment will be composed of four interconnected thread courses extending longitudinally of the conductor. To condition the coverings on different electrical conductors with various color combinations, threads of different colors may be used. For example, the alternate threads, if so desired, may be white and red, resulting in alternate thread courses of the covering being white and red in color.

In order that the color combinations used in the coverings may be more readily observed at a glance in identifying one conductor from another the oscillating means is employed. During the rotation of the eccentric 84 the bell-crank lever 87 is rocked about its pivot and in a similar manner, through the connection of the link 90, the gear segment 89 is rocked, causing rotation of the element 13 and member 65 in one direction for a predetermined distance and alternately in the opposite direction for a predetermined distance, moving therewith the cams 40 and 41 and thread guides 52. The oscillating motion of the cams 40 and 41 and thread guides 52 takes place during the continued rotation of the needle carrier, varying the thread positions with the associated portions of the cams, resulting in the forming of irregular or zigzag thread courses in the covering formed upon the conductor. This form of covering is illustrated in Fig. 4, the irregular courses being indicated by reference numeral 95. With the zigzag courses it is possible to readily observe the colors of more than one course at a glance and thus avoid confusing one conductor with another when both colors are not readily observed.

The embodiment of the invention herein disclosed is illustrative only and may be widely modified and departed from in many ways without departing from the spirit and scope of the invention as pointed out in and limited only by the appended claims.

What is claimed is:

1. In a knitting apparatus, needles, a rotary carrier therefor, means to guide threads to the needles at predetermined positions, means to cause actuation of the needles at the thread positions, and means to cause oscillation of the thread positions.

2. In an apparatus for forming a covering on a core, thread supplies, means to guide threads from the supplies to predetermined positions, knitting needles, a carrier to position the needles about a core to engage the threads at the said thread positions, means to cause actuation of the needles to knit a covering of interconnected thread courses with the threads on the core, and means to cyclically vary the said thread positions to vary the directions of the thread courses.

3. In an apparatus for forming a covering on a core, thread supplies, means to guide threads from the supplies to predetermined positions, knitting needles, a carrier to position the needles about a core to engage the threads at the said thread positions, means to cause actuation of the needles to knit a covering of interconnected thread courses with the threads on the core, and means to intermittently vary the said thread positions and the needle actuating means

to cause actuation of the needles at the varying thread positions.

4. In an apparatus for forming a covering on a core, thread supplies, means to guide threads from the supplies to predetermined positions, knitting needles, a carrier to position the needles about a core to engage the threads at the said thread positions, means to cause actuation of the needles to knit a covering of interconnected thread courses with the threads on the core, and means to cause oscillatory movement of the thread positions and the needle actuating means to cause the thread courses to lie in zigzag paths longitudinally of the core.

5. In an apparatus for forming a covering on a core, knitting needles, a carrier therefor rotatable about a core to be covered, threads, means to guide the threads to predetermined positions relative to the carrier, elements to cause actuation of the needles to knit a covering of interconnected thread courses with the threads on the core, and means to cause simultaneous movement of the guide means and the elements to cause cyclic variation in the directions of the thread courses on the core.

6. In an apparatus for forming a covering on a core, knitting needles, a carrier therefor rotatable about a core to be covered, threads of selected varying colors, means to guide the threads to predetermined positions relative to the carrier, elements to cause actuation of the needles to knit a covering of interconnected thread courses with the threads on the core, and means to cause simultaneous movement of the guide means and the elements to cause cyclic variation in the directions of the thread courses on the core.

7. In an apparatus for forming a covering on a core, knitting needles, a carrier therefor rotatable about a core to be covered, threads, means to guide the threads to predetermined positions relative to the carrier, elements to cause actuation of the needles to knit a covering of interconnected thread courses with the threads on the core, and means to cause oscillatory move-

ment of the guide means and the elements to cause variation in the directions of the thread courses on the core.

8. In an apparatus for forming a covering on a core, knitting needles, a carrier therefor rotatable about a core to be covered, means to rotate the carrier, threads, means to guide the threads to predetermined positions relative to the carrier, elements to cause actuation of the needles to knit a covering of interconnected thread courses with the threads on the core, and means operatively connected to the said rotating means to cause simultaneous oscillatory movement of the guide means and the elements to cause variation in the directions of the thread courses on the core.

9. In an apparatus for forming a covering on a core, thread supplies, means to direct threads from the thread supplies to definite positions about a core, means to knit a covering of interconnected thread courses with the threads at the said positions on the core, and means to oscillate the directing means to cause the thread courses to lie in zigzag paths longitudinally of the core.

10. In an apparatus for forming a covering on a core, thread supplies of selected varying colors, means to direct threads from the thread supplies to definite positions about a core, means to knit a covering of interconnected thread courses of varying colors with the threads at the said positions on the core, and means to oscillate the directing means to cause the thread courses to lie in zigzag paths longitudinally of the core.

11. In an apparatus for forming a covering on a core, knitting needles, thread supplies of selected varying colors, a carrier to position the needles about a core, means to actuate the needles to form a covering of interconnected thread courses with the threads of the thread supplies on the core, and means to cause oscillation of the thread supplies to cause the thread courses to lie in zigzag paths longitudinally of the core.

BEN K. FORD.
